UNITED STATES PATENT OFFICE.

EDWARD A. TUTTLE, OF NEW YORK, N. Y.

EXERCISING-MACHINE.

SPECIFICATION forming part of Letters Patent No. 225,736, dated March 23, 1880.

Application filed September 30, 1879.

To all whom it may concern:

Be it known that I, EDWARD A. TUTTLE, of New York, in the county and State of New York, have invented a new and Improved Exercising-Machine, which is fully described in the annexed specification.

My invention consists of a contrivance of levers and handles with the platform, whereby the elevation of the person of the operator 10 may be effected by pushing downward on the handles, the object being to afford exercise to the muscles not brought into action by the common lifting process; and it also consists of apparatus for this method of exercise and 15 the ordinary lifting apparatus, combined with one and the same platform, thereby affording both methods of exercise in one machine.

Figure 1 is a side elevation of my improved exercising-machine. Fig. 2 is a plan view. 20 A is the platform, which is pivoted at B to a pair of levers, C, which have their fulcrums at D in standards E of the base F, with which are the usual parallel bars K, to keep the platform level, and at the opposite side of pivots 25 B levers C are provided with a pair of lifting-handles, G, in about the same arrangement as exercising-machines now in use for lifting oneself while standing on the platform at O, said handles being adjustable along the slot- 30 ted portions H of the levers to vary the lever-age.

To the machine thus constructed I make the extensions I of the levers C beyond the fulcrums D—that is, opposite to the pivots B 35 and handles G—and attach to said extensions the pushing-handles J, the same being located suitably for the convenient use of the operator, when on that end of the platform at P, to elevate it with himself thereon by pushing 40 downward on said handles; and in order to secure these handles in an upright position, to prevent them from turning out of line, as they would if pivoted to a single lever, I have ar-

ranged the extensions Q of the bars K parallel with extensions I of levers C, and coupled 45 the lower portions, L, of said handles to both of said extensions, which maintains the handles in vertical lines with sufficient rigidity while the levers swing up and down. To shift them along the levers they are pivoted to the 50 slides M, fitted in the slots of the levers and provided with clamp-screws N, to set them at any point. The bars K are pivoted to standards E, like the main levers C, and to brackets R, projecting from the platform. 55

Thus I provide a machine whereon one can raise himself either by lifting or pushing downward, and exercise two different sets of muscles, with but little more expense than of a machine for either purpose alone, and two 60 persons can exercise on this machine at once.

Having thus described my invention, what I claim, and desire to secure by Letters Patent, is—

1. In an exercising-machine, the pushing-handles J, coupled with the levers C on that side of the fulcrum opposite the pivotal connections with the platform, whereby the operator is enabled to raise said platform, on which he stands, by simply pushing down on 70 the handles, as described. 65

2. The parallel bars K, extended beyond the fulcrums, along the levers C I, to the pushing-handles, and said handles connected to them and to the levers C I, substantially as de- 75 scribed. 75

3. The combination, with the platform A, levers C I, and the parallel bars K, of lifting-handles G on one side of the fulcrum D, and pushing-handles J on the opposite side, sub- 80 stantially as described. 80

EDWARD A. TUTTLE.
